An ornamental design for a blade as shown and described.

DESCRIPTION

FIG. 1 is a perspective view of a blade in accordance with the present invention;

FIG. 2 is a top view thereof;

FIG. 3 is a bottom view thereof;

FIG. 4 is a right side view thereof;

FIG. 5 is a left side view thereof;

FIG. 6 is a rear elevational view thereof; and,

FIG. 7 is a front elevational view thereof.

The broken lines illustrate the environment of the blade and form no part of the claimed design.
